CLAIM

The ornamental design for a tape display card assembly for hanging and free standing, as shown and described.

DESCRIPTION

FIG. 1 is a front view of the new design for a tape display card assembly for hanging and free standing.

FIG. 2 is a rear view thereof;

FIG. 3 is a top view thereof;

FIG. 4 is a bottom view thereof;

FIG. 5 is a side view thereof; and,

FIG. 6 is a perspective view thereof.

The broken lines in the drawings are for illustrative purposes only and form no part of the claimed design.
